UNITED STATES PATENT OFFICE.

JOHN RAPHAEL ROGERS, OF BROOKLYN, NEW YORK, ASSIGNOR TO MERGENTHALER LINOTYPE COMPANY, A CORPORATION OF NEW YORK.

TYPOGRAPHICAL MACHINE.

1,116,489.

Specification of Letters Patent. Patented Nov. 10, 1914.

Application filed July 24, 1911. Serial No. 640,082.

To all whom it may concern:

Be it known that I, JOHN RAPHAEL ROGERS, a citizen of the United States, and a resident of Brooklyn, county of Kings, and State of New York, have invented a new and useful Improvement in Typographical Machines, of which the following is a specification.

My invention relates to typographical machines, and more particularly to that class thereof known to the public under the name "Linotype", as illustrated for instance in U. S. Letters Patent to O. Mergenthaler No. 436,532.

In the form herein illustrated and described, the machine is provided with a plurality of magazines, and more specifically, the invention relates to the distributing mechanism therefor. In this machine the matrices are lifted in the usual manner by the second elevator for distribution, and pass therefrom onto a primary distributor where they are separated according to font for the different magazines. When thus separated they next drop through matrix conveying tubes to the individual distributor boxes, of the kind shown in U. S. Letters Patent to D. S. Kennedy No. 849,795, and in my pending application Serial No. 640,081 filed July 24, 1911. From the distributor box the matrices are then elevated one by one to the magazine distributing apparatus, wherein they are advanced along a distributor rail by the customary feed screws until they reach the appropriate magazine channels, into which they drop in the manner well understood in the art.

In the accompanying drawing I have shown the machine as equipped with four magazines for the matrices and consequently with four systems of distributing apparatus, one for each of the magazines. In ordinary practice it often happens that it is necessary to obtain access to the interior of the machine for the purpose of regulating or adjusting the mechanism or to dislodge improperly located matrices therein.

It is therefore one of the principal features of my invention to arrange the distributing apparatus, and also the several banks of magazine entrances, so that they may be readily moved from operative position, and afterward returned thereto and be securely held in place.

In the accompanying drawing I have shown my invention in preferred form, but

obviously many changes and variations may be made therein without departing from its spirit, and generally speaking I desire it to be understood that I do not limit myself to any specific form or embodiment except in so far as such limitations are specified in the claims.

Referring to the drawings: Figure 1 is a rear perspective view of the magazines and distributing devices of a linotype machine; Fig. 2 is a similar view of a portion of the same, on an enlarged scale and showing the parts opened out to give access to the interior; and Fig. 3 is a diagrammatic end view illustrating some of the principal features of my invention.

The previously mentioned font separating devices A are mounted upon the main frame A' and operate in substantially the same manner as disclosed in my previous Letters Patent No. 890,303, and in my application filed July 20, 1911, Serial No. 639,588. As the construction and operation of the font separator are not essential to an understanding of my present invention, it will not be further described herein, as reference may be had to the said patent and application for the details thereof. After the matrices leave the font separator, they pass through tubes B to the distributor boxes C, from which they are delivered to the magazine distributing devices, also in the manner set forth in my said application; and as these features are similarly immaterial to the present invention, they will not be described at length herein.

As previously stated, the matrices are delivered from the boxes C to the ordinary distributing devices, comprising the distributor rails G and distributor screws F, which advance the matrices thereon until they reach their proper channels in the several magazines D. In the present instance four such magazines are illustrated, and there are consequently a corresponding number of distributing devices therefor. Motion is imparted to the distributing mechanism by the belt M, pulley M¹, sprocket gearing M², and suitable gearing M³, whereby the distributor screws F are rotated and the connected parts actuated. These power transmitting means and gearing are and may be of any suitable or desired form, and as in themselves they constitute no part of the present invention, they are only conventionally illustrated in

the drawings. It is to be noted that these several distributing devices, including the screws F and the actuating gearing therefor, the distributor rails G, the distributor boxes C, and the matrix conveying tubes B, are all of them carried by and connected to the movable frame H. The frame H is mounted by arms H¹ upon the shaft H², suitably journaled in the main frame A¹, and in such manner that the frame, together with all of the distributing mechanism thereon, may be turned upwardly and over its pivotal support from the normal position shown in Fig. 1 to that illustrated in Fig. 2. It may be held in its lifted position by any suitable means, such for instance as the hook H²⁰, (see Fig. 1). It will be seen that the pivotal support of the frame H is concentric with the pulley M¹ and the driving element of the sprocket gearing M², so that when the frame is swung to its upward position, as shown in Fig. 2, there is no interference with the ordinary relations of the power connections. It will also be noted that I have provided counter-balancing means to offset the considerable weight of the frame H and the distributing devices carried thereby. These means consist of a strong spiral spring H³, contained within the tube H⁴ and encircling the pivotal shaft H², one end of the spring being connected to a stationary portion and the other to the shaft H² in such manner that the force of the spring is applied to counter-balance the weight of the frame H and the parts thereon.

It will be noted of course that when the frame H is swung upwardly, the tubes B mounted thereon will be carried out of operative relation to the font separating mechanism A, the location of the tubes on the frame being such that this upward movement of the frame will be permitted without danger of the tubes engaging the font separating mechanism or any other obstructing part of the machine. This feature is of advantage in that it permits the movement of the distributors without the necessity for any preparatory movement of other parts. The mounting of the tubes B upon the frame H is further advantageous in the respect that they may thus remain connected to the distributor boxes C which are also carried by the frame.

I have also provided somewhat similar means to permit the ready removal of all the magazine entrances E¹ from normal position, in order to give access thereto and to the mouths of the magazines D. As shown in Fig. 2, the magazine or channel entrances E¹ are all carried by a movable frame E, which is supported upon arms E⁵ pivotally mounted at E⁶ upon the main frame A¹. Due to this pivotal arrangement, the frame E with the connected magazine

entrances may be moved from its normal position, as shown in Fig. 1, to its opened-out position, as shown in Fig. 2, and thus access is given to the magazines, etc. In order to compensate for the considerable weight of the frame E, I employ counter-balancing means in connection therewith. Connected to the arms E², E², are arms E³, E³, at the opposite side of the pivots E⁶, E⁶, thereby constituting levers turning about the pivots as fulcra. To the ends of each of the arms E³, E³, are connected chains or belts E⁴, E⁴, which pass downward and about pulleys E²⁰, E²⁰, and are connected from the opposite sides by a powerful spring E⁸ (see Fig. 1.) It will be seen that when the frame E is moved downward to the position shown in Fig. 2, the arms E³, E³, will be lifted, thus pulling upon the chains or belts E⁴, E⁴, and distending the spring E⁸ in such manner as to counter-balance the weight of the frame E.

When the frame E is located in its normal operative position, it is held therein by a locking arm J pivoted at J¹ to the magazine frame and engaging the frame E by a locking notch and stud J², see Fig. 3. When the frame H carrying the distributing mechanisms is in its lower or operative position, it is locked and held therein by the engagement of one or more latches H⁵ with corresponding locking notches E¹⁰ upon the frame E. It will be seen that in this manner the several parts are firmly held in operative relations to each other, and that upon their disengagement they may be readily opened out so as to give complete access thereto, as well as to other interior devices. Fig. 3 shows this capability diagrammatically, the operative positions being indicated therein by full lines, and the opened-out or inoperative positions by dotted lines.

Having thus described my invention, its construction and mode of operation, what I claim and desire to secure by Letters Patent of the United States is as follows:

1. In a typographical machine, the combination of a plurality of distributor bars, a series of rotary screws for propelling the matrices along the bars, the said screws being geared together so as to rotate in unison, and a common supporting frame upon which said parts are mounted, the said frame being movable at will from its operative position to give access to the distributor bars and the other parts.

2. In a typographical machine, the combination of a plurality of distributor bars, a series of rotary screws for propelling the matrices along the bars, the said screws being geared together so as to rotate in unison, and a common supporting frame upon which said parts are mounted, the said frame being pivotally connected to the ma-

- chine frame so as to swing upwardly from its operative position to give access to the distributor bars and the other parts.
3. In a typographical machine, the combination of a plurality of distributing mechanisms, a font separating mechanism, a tube or conductor leading from the font separating mechanism to each of the distributing mechanisms, and a common supporting frame upon which all of the distributing mechanisms are mounted, the said frame being movable at will from its operative position to give access to the distributing mechanisms and the other parts.
- 15 4. In a typographical machine, the combination of a plurality of distributing mechanisms, each comprising a distributor box for delivering the matrices individually thereto, a font separating mechanism, a tube or conductor leading from the font separating mechanism to each of the distributor boxes, and a common supporting frame upon which all the distributing mechanisms and their distributor boxes are mounted, the 25 said frame being movable at will from its operative position to give access to the distributing mechanisms and the other parts.
5. In a typographical machine, the combination of a plurality of distributing mechanisms mounted to swing upwardly as a whole from their operative position, a font separating mechanism, and a tube or conductor leading from the font separating mechanism to each of the distributing mechanisms, the said tubes being mounted so as to be movable out of operative relation to the font separating mechanism to permit the upward movement of the distributing mechanisms.
- 40 6. In a typographical machine, the combination of a plurality of distributing mechanisms, a common supporting frame therefor mounted to swing upwardly from operative position, a font separating mechanism, and a tube or conductor leading from the font separating mechanism to each of the distributing mechanisms, and the said tubes being mounted upon the distributor supporting frame and adapted to be moved out of operative relation to the font separating mechanism by the upward movement of said frame.
- 45 7. In a typographical machine, the combination of a plurality of distributing mechanisms movable upwardly as a whole from their operative position, a font separating mechanism, and a series of tubes or conductors leading from the font separating mechanism to the several distributing mechanisms, one of the last mentioned elements being mounted so as to be movable out of operative relation to the other to permit the free upward movement of the distributing mechanisms.
8. In a typographical machine, the combination of a plurality of distributing mechanisms movable as a whole from their operative position, and a font separating mechanism adapted to deliver type or matrices to one or another of the distributing mechanisms according to font, the said parts being arranged relatively so as to permit the movement of the distributing mechanisms without disturbing the position of the font separating mechanism.
- 65 9. In a typographical machine, the combination of a magazine entrance, a supporting frame therefor movably connected to the machine frame, a contractile spring, and connections between the opposite ends of the spring and the supporting frame, whereby the movement of the supporting frame will pull the spring in opposite directions and thereby cause it to exert a counterbalancing effect upon the supporting frame and its connected parts.
- 75 10. In a typographical machine, the combination of a magazine entrance, a pivoted supporting frame therefor provided at opposite sides with rock arms pivotally connected to the machine frame, and a spring having its opposite ends connected to the rock arms so as to be placed under tension by the movement of the supporting frame, and thereby caused to exert a counterbalancing effect upon the supporting frame and its connected parts.
- 80 11. In a typographical machine, the combination of the magazine entrance E^1 , its supporting frame E pivotally connected to the machine frame so as to be swung backward and downward, the rock arms E^3 on opposite sides of the supporting frame and extending forwardly from its pivotal point of connection, the counterbalancing spring E^6 , the chains E^4 connecting the opposite ends of the spring to the rock arms E^3 , and the pulleys E^{20} over which the chains travel.
- 100 12. In a typographical machine, the combination of a plurality of magazine entrances movable downwardly as a whole from their operative position, and having their receiving ends arranged one behind and below another, and a plurality of distributing mechanisms arranged in like order, the said distributing mechanisms being movable as a whole from their operative position to permit the aforesaid movement of the magazine entrances.
- 110 In testimony whereof I hereunto set my hand this 22nd day of July, 1911, in the presence of two attesting witnesses.
